WHIP ROLL BEARING

Frank J. Upchurch, Charlotte, N. C., assignor to
D. & S. Engineering Company, Charlotte, N. C.,
a corporation of North Carolina

Application April 27, 1949, Serial No. 89,963

2 Claims. (Cl. 139—114).

1

This invention relates to textile machinery and more especially to improved insertable bearings for supporting a whip roll or whip roll shaft on a loom.

In many loom structures, the warp is drawn, under tension, from a conventional warp beam in a vertical direction and then passes over a vibrating whip roll and through conventional heddles, after which it extends to a reed for weaving cloth from the warp yarns in the usual manner.

In order to maintain a uniform tension in the warp yarns with vertical reciprocation of the heddles it is necessary that the vibrating whip roll be mounted for oscillation on an eccentric pivot so it can be raised or lowered to compensate for variation in the warp. The whip roll pivot is usually supported by a pair of brackets or arms disposed adjacent the loom side frame members and these brackets are, in turn, mounted on a whip roll shaft oscillatably mounted in brackets secured to proximate sides of the loom frame members. Heretofore the brackets for supporting the vibrating whip roll pivot, as well as the brackets for supporting the whip roll shaft, have either been provided with a plurality of notches in their upper ends in which the vibrating whip roll pivot was mounted, or, in other instances, these brackets have been provided with flat bottomed notches in the upper ends thereof into which wooden bearing blocks have been mounted for oscillatable reception of the vibrating whip roll pivot.

It is an object of this invention to provide bearing blocks which supplement the wooden blocks heretofore described, these bearing blocks being provided with semi-circular inserts or bearing members of a preferred bearing material such as bronze, brass and the like.

It is another object of this invention to provide a removable bearing block which is adapted to be mounted on the usual vibrating whip roll pivot bracket, this bracket usually being provided with a pair of semi-circular notches in its upper end in either one of which the eccentric pivot of the vibrating whip roll is mounted for oscillation. In this instance, the conventional vibrating whip roll pivot bracket is modified in that the portion which separates the notches is removed thus providing the bracket with a single elongated notch and the improved bearing block is fitted to this notch.

This improved bearing block is provided with a single notch in its upper face which corresponds to one of the notches previously

2

appearing in the whip roll pivot bracket. A semi-circular bearing member, of a preferred bearing material such as brass, bronze and the like, is inserted in the bottom of the notch in the improved bearing block and the pivot for the vibrating whip roll is mounted for oscillation thereon. If so desired, the improved bearing block may be turned 180 degrees on its vertical axis to thus position the notch appearing therein 10 in the same position the previous other of the notches occupied in the original bracket for the vibrating whip roll pivot.

Some of the objects of the invention having been stated, other objects will appear as the description proceeds, when taken in connection with the accompanying drawings, in which:

Figure 1 is a side elevation of a portion of a loom showing the conventional form of whip roll shaft bracket and my improved vibrating whip roll pivot bracket associated therewith;

Figure 2 is a fragmentary plan view taken substantially along the line 2—2 in Figure 1;

Figure 3 is an enlarged elevation showing the vibrating whip roll pivot bracket and the improved bearing block mounted therein and also showing the whip roll shaft and the vibrator roll pivot in cross section and is taken substantially along the line 3—3 in Figure 2;

Figure 4 is a view similar to Figure 3 but showing the improved bearing block in an alternate position;

Figure 5 is another side elevation of a portion of a loom showing a modified form of the removable bearing block as applied to both the whip roll bracket and the vibrating whip roll pivot bracket;

Figure 6 is a fragmentary top plan view taken substantially along the line 6—6 in Figure 5;

Figure 7 is an enlarged elevation showing a 40 vibrating whip roll pivot bracket which is slightly different from the vibrating whip roll pivot bracket shown in Figures 3 and 4 and showing the modified form of the bearing member as applied thereto and taken substantially along the line 7—7 in Figure 6;

Figure 8 is a vertical sectional view on a slightly reduced scale and is taken substantially along the line 8—8 in Figure 7 and showing a portion of the vibrating whip roll pivot associated therewith;

Figure 9 is an enlarged vertical sectional view through one of the conventional whip roll shaft brackets and showing the modified form of the bearing block associated therewith and is taken 55 substantially along the line 9—9 in Figure 5.

Referring more specifically to the drawings, the numeral 10 indicates one of the side frames of a loom of a type such as manufactured by the Draper Corporation of Hopedale, Massachusetts, and is known as their Model XD loom. The loom frame member 10 carries a conventional driven rotating crankshaft 12 having a hand wheel 13 fixedly mounted on one end thereof and also having a cam wheel 14 mounted adjacent the hand wheel 13 and being fixedly mounted on the end of the crankshaft 12.

A conventional whip roll cam follower arm 15 extends beneath the end of the crankshaft 12 shown in Figure 1 and engages the cam wheel 14. The right-hand end of the whip roll cam follower arm 15 is fixedly mounted on an extended shaft portion 17 of a conventional eccentric pivot member 18 to which one end of a conventional vibrating whip roll 21 is secured as by a screw 22. The opposite end of the vibrating whip roll 21 is not shown inasmuch as it is mounted in an identical manner to the manner shown in Figure 2 and an illustration and description of the same is deemed unnecessary.

The pivot member 18 is oscillatably mounted in an improved bearing member to be later described and which is carried by a vibrating whip roll bracket broadly designated at 25. This vibrating whip roll bracket 25 has an enlarged boss 26 at its left-hand end in Figures 2, 3 and 4 which is fixedly mounted as by a set screw 27 on a conventional whip roll shaft 30 oscillatably mounted in a conventional whip roll shaft bracket 31 provided with a plurality of semi-circular notches 32 in its upper face for reception of the whip roll shaft 30. The conventional whip roll shaft bracket 31 is secured as by a bolt 34 to the inner surface of the side frame member 10. It is to be understood that the other end of the whip roll shaft 30 is mounted in an identical manner to that shown in Figure 2 except opposite hand.

The conventional whip roll shaft 30 has a conventional whip roll lever collar 35 fixed on its lower end in Figure 2 and against which the upper end of a conventional whip roll lever 36 is secured as by a screw 37 which is threadably imbedded in the end of the shaft 30.

Whip roll arms such as the bracket 25 are usually provided with a pair of semi-circular notches in their upper right-hand ends in Figures 3 and 4. However, in this instance, the portion which defines the proximate surfaces of the two notches is removed from the bracket 25 and the bracket 25 is thus formed with an elongated notch 40 in its right-hand end in Figures 3 and 4.

One form of the present invention comprises a bearing block 41 which is fitted to the notch 40 formed in the right-hand portion of the bracket 25, in Figures 3 and 4, and has a semi-circular notch 42 cut in its upper surface and extending across the bearing block 41. The bearing block 41 is also provided with a pair of projections 43 disposed at the upper edges of the semi-circular notch 42. A semi-circular bearing member 45, whose outer periphery conforms to the curvature of the bottom of the notch 42, is inserted in the notch 42 and is held therein by a pressed fit between the bottom of the notch 42 and the lower surfaces of the projections 43. This semi-circular bearing member 45 is preferably of bronze, brass, babbitt or other bearing material inasmuch as the shaft portion 17 of the eccentric pivot member 18 is mounted for oscillation on this semi-circular bearing member 45 and is usually

5 of cast iron and it is preferred that the semi-circular bearing member 45 be of a softer material than the shaft carried thereby so that the bearing 45 will wear rather than the shaft 17 and may be replaced with a minimum of labor and expense.

10 The lower surface of the bearing block 41 is provided with a pair of threaded bores 47 and 48 and the lower right-hand portion of the bracket 25 is slidably penetrated by a screw 50 which threadably engages the threaded bore 47 in the instance of the bearing block 41 being mounted in the bracket 25 with its semi-circular cavity 42 being disposed to the right of the center of the notch 40 in the bracket 25 as shown in Figure 3.

15 However, in the event the operator of the loom desires to position the eccentric member 18 closer to the front of the loom, as is often the case, the bearing block 41 is then turned around and placed in the notch 40 in the manner shown in Figure 4 and, in this instance, the screw 50 would threadably engage the threaded bore 48 rather than the threaded bore 47 for securing the block 41 to the bracket 25. It is thus seen that the bearing block 41, in conjunction with the bracket 25 as shown in Figures 3 and 4, will serve the same purpose as the original bracket that this bracket 25 is adapted to replace and which had a pair of semi-circular notches in the upper surface thereof. It is manifest that a bearing block 25 of the type shown in Figures 3 and 4 may also be applied to vibrating whip roll brackets which may, heretofore, have been worn to such an extent that they would have to be discarded and, 20 in the event of the bracket being used such as that shown in Figures 3 and 4, the life of this bracket 25 and its bearing block 41 would be unlimited, it merely being necessary to replace the semi-circular bearing member 45 as it becomes worn.

Modified form

25 Since many looms are not identical, another form of the invention is shown in Figures 5 to 9, inclusive, said invention being applied to a loom such as is manufactured by the Draper Corporation and is known as their Model XK loom. In Figure 1, the invention is shown as it is applied to the left-hand side of a loom, however, in Figure 5, the modified form of the invention is shown as being applied to the right-hand side of a loom. With this exception, the conventional structure of the loom in Figures 1 and 5 is substantially the same and therefore those parts in Figure 5 which are similar to those shown in Figure 1 will bear the same reference characters with the letter *a* appearing after each number and therefore a further description of these like parts will not be given. It might be stated, however, that the whip roll cam follower arm 15a extends above the end of the crankshaft 12a in Figure 5 rather than below the crankshaft as the cam follower arm 15 is shown in Figure 1.

30 Referring to Figures 5 to 9, inclusive, it will be noted that the vibrating whip roll pivot bracket 25a and the whip roll shaft bracket 31a are of a substantially different structure than the vibrating whip roll pivot bracket 25 and the whip roll shaft bracket 31 in Figures 1 to 4, inclusive, and, 35 it is due to this variation in the brackets that I have provided a modified form of bearing block which may be applied to the brackets 25a and 31a without altering the brackets 25a and 31a other than removing the wooden bearings which are 40 usually provided with brackets of this type and

inserting my improved bearings in lieu thereof.

The vibrating whip roll eccentric pivot bracket 25a is usually provided with a pair of notches 60 and 61, which, in some brackets, are provided with flat bottoms and others of which have downwardly and inwardly sloping corners merging with a flat bottom. One of the ends of each of these notches 50 and 51 is usually open and the other end is partially closed by a web portion 62. Each of these notches 60 and 61 is adapted to receive an improved bearing block 63, one side of which slidably engages the inner surface of the web portion 62. These bearing blocks 63 are secured to the bracket 25a as by screws 64. The lower corners of the bearing blocks 63 are cut on an angle as at 65 so these bearing blocks 63 may be used in brackets whose notches are provided with flat bottoms all the way across the same or whose notches are provided with sloping side walls at the bottom corners thereof.

Each of the bearing blocks 63 is provided with a semi-circular notch 67 and also has projections 70 integral therewith which extend into the notch 67 at opposite sides thereof. A semi-circular bearing member 72, preferably of brass or bronze, is adapted to be inserted in the bearing block 63, its lower surface conforming to the curvature of the notch 67 and its upper edges engaging the lower surfaces of the projections 70 so as to secure the semi-circular bearing member 72 in the bearing block 63 as by a pressed fit.

The whip roll shaft bracket 31a shown in Figures 5, 6 and 9, is provided with a plurality of equally spaced notches 75 all of which are identical to the notches 60 and 61 in the bracket 25a. These notches 75 are also partially closed by a web portion 76 similar to the web portions 62 of the bracket 25a. A bearing member 77 is secured in each of the notches 75 as by a screw 80. These bearing blocks 77 are each provided with a semi-circular bearing member 78 on which the shaft 30a is oscillatably mounted. The bearing block 77 is identical to the bearing block 63, with the exception that its size may have to be varied somewhat to accommodate the notches 75 in the whip roll shaft bracket 31a. A further description of the bearing blocks 77 and the whip roll shaft bracket 31a is therefore deemed unnecessary.

In the drawings and specification there has been set forth a preferred embodiment of the invention, and although specific terms are employed, they are used in a generic and descriptive sense only, and not for purposes of limitation, the scope of the invention being defined in the claims.

I claim:

1. In a loom having a whip roll over which a warp is adapted to pass, said loom also having a whip roll shaft supported by the loom, means for supporting the ends of the whip roll comprising a bracket fixedly mounted at one end thereof on one end of the whip roll shaft and extending outwardly and upwardly from the whip roll shaft, said bracket having an elongated

notch in its upper face extending longitudinally of the bracket, a bearing block, said bearing block having a transverse notch in its upper face and said transverse notch being positioned to one

- 5 side of the longitudinal center of the block, a semi-circular bearing member mounted in the semi-circular notch in the block and on which the end of the whip roll may be oscillatably mounted and means projecting into the notch
 10 in the block for confining the semi-circular bearing member therein, said bearing block having two spaced threaded bores in its lower portion, said bracket having a projection extending upwardly from its bottom surface for entering one
 15 of the threaded bores in the bearing block, said bracket also having a vertical bore therethrough for reception of a screw which is adapted to enter the other threaded bore in the bearing block.
 20 2. In a loom having a whip roll over which a warp is adapted to pass, said loom also having a whip roll shaft supported by the loom, means for supporting the ends of the whip roll comprising a bracket fixedly mounted at one end thereof
 25 on one end of the whip roll shaft and extending outwardly and upwardly from the whip roll shaft, said bracket having an elongated notch in its upper face extending longitudinally of the bracket, a bearing block and means for securing the bearing block in the notch of the bracket, said bearing block having a transverse notch in its upper face and said transverse notch being positioned to one side of the longitudinal center
 30 of the block and a semi-circular bearing member mounted in the semi-circular notch in the block and on which the end of the whip roll may be oscillatably mounted and means projecting into the notch in the block for confining the semi-circular bearing member therein, said means for securing the bearing block in the notch of said bracket comprising a substantially vertically extending screw mounted in said bracket and penetrating the notch in the bracket in off center relation lengthwise of the notch, said bearing block
 35 having a pair of threaded bores in its lower surface, whereby one of the bores may be threadably penetrated by the screw for securing the bearing block to the bracket and, when desired, the screw may be removed from the first of the threaded bores and then the bearing block may be turned
 40 180 degrees so as to align the other of the threaded bores with the screw and to thus change the position of the semi-circular bearing member in the bearing block as the bearing block is secured to the bracket.
